UNITED STATES PATENT OFFICE.

GEORGE RAMSEY, OF BROOKLYN, NEW YORK, ASSIGNOR TO ANCHOR CAP & CLOSURE CORPORATION, OF LONG ISLAND CITY, NEW YORK, A CORPORATION OF NEW YORK.

FRictional Sealing Closure.

Application filed September 21, 1922. Serial No. 589,584.

To all whom it may concern:

Be it known that I, GEORGE RAMSEY, a citizen of the United States, residing at Brooklyn, in the county of Kings, State of New York, have invented certain new and useful Improvements in Frictional Sealing Closures, of which the following is a specification.

This invention relates to closures and more specially to closures of the friction type.

The principal object of the invention is the provision of a closure which may be applied to a vessel by a simple operation not necessitating special machinery, and which will retain its place until intentionally removed, and which may be replaced as desired to re-seal the package.

A more particular object of the invention is the provision of a closure cap having the characteristics above specified, which is adapted to accommodate a maximum range of variation in size and contour of the kind of vessels for which it is designed, and provide an effective closure and seal upon such various vessels.

Another particular object is the provision of a cap having the aforementioned characteristics, which is so constructed as to facilitate its being forced to sealing position on a vessel, and to safeguard it against unintentional distortion in such operation.

Another object is the provision of such a cap, wherein the construction is such as to facilitate the exhaustion of air from the vessel to which it is applied, preliminary to the movement of the cap to sealing position.

Other and further objects and advantages of the invention will be obvious upon an understanding of the illustrative embodiments now about to be described, or will be pointed out or indicated hereinafter in the specification or the appended claims, or appear from the accompanying drawings forming a part of this application.

In the drawings is illustrated the preferred form in which the invention may be embodied, together with certain modifications. It is to be understood, however, that the several species therein illustrated are not regarded or intended as exhaustive of the varieties of forms in which the invention may be embodied.

In said drawings Figure 1 represents a side elevational view, partly in section, of a

form of closure cap embodying features of the invention;

Figure 2 is a fragmentary elevational section illustrating the association of such a cap with a suitable vessel, preliminary to its being moved to sealing position, the parts being shown in exaggerated scale and proportion;

Figure 3 is a similar fragmentary sectional elevation showing, in exaggerated scale and proportion, the relationship of the cap and the vessel when the former is in sealing position upon the latter;

Figure 4 is a fragmentary cross section taken substantially on line 4—4 of Figure 1;

Figure 5 is a detail in the nature of a part elevation of a modified form;

Figure 6 is an elevational view, partly in section of a second modification; and

Figure 7 is a detail of a portion of the cap shown in Figure 6, with the cap on a suitable vessel.

Described generally, the invention contemplates a closure in the nature of a cap which is provided with a peripheral skirt portion, which may be formed integrally with or separately from a cover portion designed to close the mouth of a vessel. The skirt portion provides a constraining member adapted to engage the wall of the vessel under tension induced by the movement of the closure on to the vessel by force exerted longitudinally of the axis of the latter. The constraining member is characterized by being formed with a continuous contact member which is resilient, and which is designed to engage the wall of the vessel under resilient tension in such fashion as to hold the closure on the vessel and provide a sealing zone between the two under suitable compression to insure close and uniform contact. In order to increase the adaptability of the constraining member to the contour of the vessel, it is provided with a number of transversely

extending corrugations, which have the effect of increasing the circumferential expansibility of the constraining member, which permits the contact member being pre-formed on a considerably smaller circumference, or shorter radius, than the wall portion of the vessel upon which it is designed to seat, with the result that, when the cap is forced on the vessel, a high tension is induced in the constraining member as a

whole without reaching the limit of elasticity of the material. This secures closer contact of the contact member with the vessel wall, and causes it to conform to all irregularities in its contour. Moreover, it enables caps of a given size to be utilized in sealing vessels of a given commercial size which vary materially in actual measurement at the sealing zone.

10 To facilitate the forcing of the closure to sealing position on the vessel, the constraining member is provided with a plurality of corrugations or inwardly extending supporting projections formed below and contiguous 15 to or as a part of the contact member, and said supporting projections are spaced apart about the circumference of the constraining member, and have sloping or tapering lower extremities disposed toward the lower margin 20 of the constraining member in such position as to engage the vessel at separated points.

These separate projections have a two-fold function; they form temporary spacing 25 supports for the cap upon the vessel, holding the major portion of the cap out of contact therewith, so that the air may be exhausted preliminary to the movement of the cap toward the sealing position, and they 30 act as wedging members or inclined planes effective to induce the tension in the constraining member gradually as the cap is moved to sealing position. Because of this last function, the amount of force necessary 35 to seat the cap is less than it would be if the material in the constraining member were stretched to the full degree immediately.

The invention may be understood more 40 particularly by reference to the embodiments shown in the drawings, wherein the respective reference characters are utilized to indicate similar parts in the several views.

In Figures 1, 2, 3 and 4 is shown a form 45 of cap which may be made conveniently of any resilient sheet material such as sheet metal, properly shaped to provide a cover portion 1 and a skirt portion 2. The cover 1 may be provided with a sunken portion or 50 panel 4. The skirt is formed with a circumferentially extending inwardly protruding bead or rib 5 which may be conveniently spun or otherwise formed in the metal along substantially the median line of the skirt. 55 The lower rim of the skirt may be shaped to form a finished edge 6, in any suitable fashion such as by being turned in as shown, or by being spun into a wire edge, as shown in Figure 6. The portions of the material 60 in the skirt above and below the bead 5 are provided with interspaced transversely extending projections 7, which may be formed conveniently as short corrugations or embossments coalescing with the rib 5 but preferably of somewhat less depth than said rib,

so that their crests do not project inwardly so far as does the crest of the rib. The lower extremities of the lower series of projections 7 preferably slope outwardly to the skirt portion so as to form sloping or wedge-like supporting members. The normal peripheral wall of the skirt portion as well as the lower margin of the skirt, lie on circumferences which are conveniently larger than the peripheral circumference of the vessel for which the cap is designed, but the crests of the projections 7 lie on a circumference which is smaller than that of the intended vessel, while the crest of the rib 5, which constitutes the contact member, is disposed on a still smaller circumference; the relationship being illustrated in exaggerated proportions in Figure 2, wherein the vessel is designated by the character C. The rib 5 is preferably narrow so that its crest or contact portion will afford a narrow zone of contact upon the vessel wall, and it may be either of angular form, as illustrated in Figure 1, or of arcuate form as illustrated in Figure 5.

By virtue of this construction, as will be evident from Figure 4, the folded or zigzag form of the skirt gives it, in a fashion, the properties of a contracted spring, and increases its circumferential expansibility by permitting its diameter being increased without necessitating direct stretching of the metal. The contact portion of the rib 5, however, not being folded, is subjected to stretching when its circumferential extent is increased, so that the material is placed in a high tension which gives it an effective inward gripping action. This tension is induced in rib 5 by the operation of forcing the cap on to a suitable vessel. The operation is illustrated in Figures 2 and 3. The upper rim of the vessel being originally accommodated within the edge 6, the cap rests thereon by virtue of the contact of the sloping ends of the lower or supporting projections 7. Pressure exerted upon the cap longitudinally of the axis of the vessel will exert a wedging action on the lower projections 7, which will be effective to expand the lower skirt portion to accommodate the vessel. As the cap rides down upon the vessel the distension of the constraining member increases gradually until, when the rib 5 reaches the vessel rim, it is necessary to produce simply the requisite stretching of the material in the rib to move the cap to sealing position. This stretching of the rib 5 is accompanied by an increase in the degree of divergence of its sides as illustrated in Figure 3, the result being to rock the portions of the skirt above and below the rib into an angular relationship relative to the vessel wall, and thereby increase the gripping pressure of the projections 7 upon it. In the operation of applying

ing the cap to the vessel, the projections 7 constitute stiffening members which prevent collapse of the skirt, and they also function as struts for transmitting the pressure from the top of the cap to the rim of the vessel. The cap may be removed from the vessel either by driving it off longitudinally thereof, or by depressing the rib 5 by rolling the vessel with the periphery of the cap in contact with a hard surface.

The modification shown in Figure 5 embodies the several features and advantages of the form just described, but has the rib 5 and the projections 7 of arcuate cross-sectional form instead of angular.

In Figure 6 is illustrated a cap in which the lower edge is a wired edge 8 to provide additional strength to this edge and to give a slightly different appearance to the cap.

Figure 7 illustrates the cap shown in Figure 6, when in place on a suitable container, and shows a detail of the cap and container in cross-section.

Having thus described my invention, what I claim is:

1. In a closure for containers having a substantially cylindrical sealing surface adjacent the mouth; a skirt comprising a series of corrugations extending substantially the full height of the skirt and rendering it readily expansible through a large range to size it to the individual container to which the closure may be applied, said corrugations protruding inwardly and having crests located on a circumference smaller than the sealing wall of the container for which the closure is designed whereby the corrugations grasp the sealing wall when the closure is applied; and an annular sealing bead traversing said corrugations intermediate their ends, said bead having a continuous annular crest adapted to grasp the sealing wall, said annular crest being of smaller circumference than the line of crests of said corrugations.

2. In a closure for containers having a substantially cylindrical sealing surface adjacent the mouth; a skirt comprising a series of inwardly protruding corrugations rendering the skirt readily expansible through a large range to size it to the individual container to which the closure may be applied, and a single annular sealing bead traversing said corrugations between their ends, said bead having a continuous annular crest adapted to grasp the sealing wall of the container.

3. In a closure for containers having a substantially cylindrical sealing surface adjacent the mouth; a skirt comprising a single annular sealing bead having a continuous annular crest adapted to grasp a container sealing wall; and a series of instruck corrugations extending upwardly from said

sealing bead to a point near the cover portion, said corrugations stiffening said skirt vertically and rendering it readily expansible through a wide range to size it to the individual container to which the closure may be applied.

4. In a closure for containers having a substantially cylindrical sealing wall adjacent the mouth; a skirt comprising a series of corrugations extending upwardly from its lower edge, said corrugations having portions lying on a circumference smaller than the sealing wall of the container for which the closure is designed whereby the corrugations grasp the sealing wall of the container when the closure is applied; and a continuous inwardly protruding annular sealing bead located above said corrugations and adapted to grasp the container sealing wall; said corrugations being so located as to permit the exhaust of air from the container until the sealing bead has grasped the container sealing wall.

5. In a closure for containers having a substantially cylindrical sealing wall adjacent the mouth; a skirt comprising a series of spaced apart indentations, said indentations having portions lying on a circumference smaller than the sealing wall of the container for which the closure is designed whereby the indentations grasp the sealing wall of the container when the closure is applied; and an inwardly protruding annular sealing bead located above said indentations and adapted to grasp the container sealing wall; said indentations being so located as to permit the exhaust of air from the container until the sealing bead has grasped the container sealing wall.

6. In a closure for containers having a substantially cylindrical sealing wall adjacent the mouth; a skirt comprising a series of transverse corrugations, said corrugations having portions lying on a circumference smaller than the sealing wall of the container for which the closure is designed and tapering outwardly towards the bottom of the skirt to a circumference larger than the sealing wall of the container for which the closure is designed, whereby when the closure is applied the corrugations readily start over the sealing wall of the container and then grasp it; and an inwardly protruding annular sealing bead located above said corrugations and adapted to grasp the container sealing wall; said corrugations being so located as to permit the exhaust of air from the container until the sealing bead has grasped the container sealing wall.

7. A closure for containers comprising a cover portion adapted to close the mouth of a vessel, and a skirt portion having its normal part adapted to encompass the peripheral wall of the vessel with a clearance, said skirt portion having a part pressed inward-

ly to provide a contact member having its inner surface disposed on a smaller circumference than that of the peripheral wall surface of the vessel, the skirt portion above the 5 contact member being provided with transverse corrugations forming struts extending from the contact member to a point near the cover portion.

8. A closure cap in combination with a 10 glass container having a side wall sealing surface adjacent the mouth of the container, means on said cap in the form of corruga-

tions to provide passage ways leading to the interior of said container to permit the exhaustion of air from said container when 15 the cap is placed over the mouth thereof before the sealing operation is completed, and independent means in the form of a sealing bead in the skirt portion of said cap cooperative with said side wall sealing surface to 20 close said passage ways when said cap is sealed on said container.

GEORGE RAMSEY.
